DESIGN FOR A TOOTHBRUSH HOLDER OR SIMILAR ARTICLE

Willard R. Via, Panama City, Fla.

Application February 21, 1945, Serial No. 118,077

Term of patent 3½ years

(Cl. D4—3)

To all whom it may concern:

Be it known that I, Willard R. Via, a citizen of the United States, residing at Panama City, in the county of Bay and State of Florida, have invented a new, original, and ornamental Design for a Toothbrush Holder or Similar Article, of which the following is a specification, reference being had to the accompanying drawing, forming part thereof.

Figure 1 is a top plan view of a toothbrush holder, or similar article, showing my new design, Figure 2 is a front elevational view, and Figure 3 is a side elevational view thereof.

I claim:

The ornamental design for a toothbrush holder or similar article, as shown.

WILLARD R. VIA.
